UNITED STATES PATENT OFFICE.

ARTHUR G. WALTER, OF FREMONT, OHIO, ASSIGNOR OF ONE-HALF TO E. M. INMAN, OF FREMONT, OHIO.

BINDING MEANS FOR CHAIRS.

940,759.

Specification of Letters Patent. Patented Nov. 23, 1908.

Application filed September 8, 1908. Serial No. 452,062.

To all whom it may concern:

Be it known that I, ARTHUR G. WALTER, a citizen of the United States, and a resident of Fremont, in the county of Sandusky and State of Ohio, have invented certain new and useful Binding Means for Chairs or the Like; and I do hereby declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates particularly to means for binding together in bundles chairs of the folding type to facilitate the transportation thereof, but is not restricted to such use as it may be used for the binding together of 20 any articles for which it is adapted.

The object of my invention is the provision of simple and improved means of this class, which is efficient in its operation, easy of manipulation to engage or release a bundle of chairs, and adapted for easy adjustment to suit it for binding together different numbers of chairs.

The operation, construction and arrangement of the parts of the invention are fully 30 described in the following specification and illustrated in the accompanying drawings, in which,—

Figure 1 is a side elevation of the device comprising my invention with the parts in 35 partially open position, and Fig. 2 is a partial longitudinal section of a pile of chairs with my device in locked engagement therewith.

Referring to the drawings, *a* and *b* designate two bar members of flat or other suitable form which have their outer ends bent to form hooks *c*, *c* for engaging the rungs of the outer chairs of a pile, as shown in Fig. 2. The inner end of the bar *a* is pivoted to 45 one end of a lever-arm *d* while the inner end of the companion bar *b* is pivoted to said lever-arm a short distance from its point of connection with the bar *a*, to enable the 50 position of the two bars to be relatively adjusted by a pivotal movement of the lever arm relative to the bar *a*. The lever *d* when folded alongside of the bar *a* is retained in such position by a stud *g* on the bar engaging with an aperture *h* in the lever. The 55 lever is engaged with, or disengaged from

the stud *g* by being sprung laterally relative to the bar.

In order to enable the device to be adjusted to adapt it for binding together different numbers of chairs, the bar *b* is provided with a plurality of elongated apertures *e* disposed longitudinally thereof, any one of which may be placed in engagement with a pivot stud *f* on the side of the lever *d*, said stud having a head which is elongated 60 transversely of the lever to adapt it to pass through the apertures *e* only when the bar *b* and lever are at approximately right angles to each other.

It is apparent with this construction that 70 to bind together a number of chairs it is only necessary to link the bar *b* and lever *d* together in properly adjusted position, engage their hooked ends with the proper rungs of the outer chairs of the bundle when 75 the lever *d* is in open position, and then throw the lever to closed or folded position with the bar *a* whereby to draw the hooked ends of the bars toward each other to firmly 80 secure the chairs together.

I wish it understood that my invention is not limited to any specific construction or arrangement of the parts except in so far as such limitations are specified in the claim.

Having thus described my invention, what 85 I claim as new, and desire to secure by Letters Patent, is,—

In a device of the class described, the combination of two bar members each having its outer end formed in hooked shape and one 90 having its inner end portion provided with a plurality of longitudinally spaced openings, a lever pivoted at one end to the inner end of the other of said members and having a laterally-projecting headed lug intermediate its ends for fitting into any one of the openings in the other of said members whereby a pivotal movement of the lever relative to its attached member will effect a relative contraction or expansion of the 100 hooked ends of said members, substantially as described.

In testimony whereof I have hereunto signed my name to this specification in the presence of two subscribing witnesses.

ARTHUR G. WALTER.
